Specification for Design.

Patented July 23, 1918.

Application filed March 4, 1918. Serial No. 220,404. Term of patent 7 years.

To all whom it may concern:

Be it known that I, EDWIN C. HEATHCOTE, a citizen of the United States, residing at the city of New York, borough of Brooklyn, Kings county, in the State of New York, have invented a new, original, and ornamental Design for an Emblem, Brooch, Ring-Top, Lavallière, Button, or Similar Article, of which the following is a specification, reference being had to the accompanying drawing, forming part thereof.

In said drawing the figure is a face view of an emblem, brooch, ring-top, lavallière, button or similar article embodying or incorporating my said design.

I claim:—

The ornamental design for an emblem, brooch, ring-top, lavallière, button, or similar article as shown.

EDWIN C. HEATHCOTE.
